UNITED STATES PATENT OFFICE

2,559,170

MICROMETER CALIPER WITH BALL PIVOT
AND CAM

Herbert Pickett, Houston, Tex.

Application December 10, 1947, Serial No. 790,857

2 Claims. (Cl. 33—156)

1

The present invention relates to certain new and useful improvements in measuring instruments such as dual leg-equipped dividers, compasses and calipers and has reference in particular to micrometer-calipers used, generally speaking, for accurately measuring and determining inside and outside diameters.

An object of the invention is to structurally, functionally and otherwise improve on instruments in the stated category by adopting and using novel structural adaptations which coordinate their functions in providing efficient and structurally distinct micrometer-calipers susceptible of use with finesse and which are reliably employable in accomplishing wanted ends with requisite precision.

Another object of the invention is to provide a relatively simple frame, a pair of complementary caliper legs pivotally mounted on said frame, and micrometer type means also on the frame and mechanically coacting with inner end portions of the legs to precisely control the operation and functioning of said legs.

Other objects and advantages of the invention will become more readily apparent from the following description and the accompanying illustrative drawings.

In the drawings, wherein like numerals are employed to designate like parts throughout the views:

Figure 1 is a side elevational view of micrometer-calipers constructed in accordance with the principles of the instant invention;

Figure 2 is a central longitudinal sectional view taken on the line 2—2 of Figure 1, looking in the direction of the arrows;

Figure 3 is a sectional view at right angles to Figure 2, the section being on the line 3—3 of Figure 1, also looking in the direction of the arrows;

Figure 4 is a fragmentary elevational view;

Figure 5 is a fragmentary elevational view showing certain of the essential parts;

Figure 6 is a fragmentary elevational view of the parts assembled and focusing attention on the micrometer means;

Figure 7 is a fragmentary horizontal section taken on the line 7—7 of Figure 1, looking in the direction of the arrows.

Referring now to the drawings by distinguishing reference numerals and complementary lead lines it will be seen that the aforementioned frame is denoted by the numeral 8 and is of inverted U-shaped form, the parallel limb portions being denoted by the numerals 9 and these hav-

2

ing their free ends connected one with the other by way of a bolt or equivalent fastener 10. The bight portion 11 is provided at a point centrally between the limb portions with an integral stud 12 and this is axially socketed and screw threaded as at 13. On its exterior surfaces I provide gradations 14 with appropriate ordinals providing suitably functioning scales.

Before describing the so called micrometer mechanism I will cover the caliper legs 15, said legs, in the drawings, being shown for outside diameter measurement purposes. Obviously, however, by properly redesigning the legs they may then be employed for inside diameter measurements. The actuatable ends of the legs are considerably widened, as seen in the drawings and have assembling and stabilizing adapters 16 of arcuate form connecting respectively with predetermined marginal portions of assembling disks 17. The disks 17 of the respective legs are disposed in spaced parallelism between the limb portions 9 of the U-frame and are provided in their outer surfaces and at their immediate centers with depressions which are lined up with similar depressions in the limb portions to accommodate jointing and pivoting balls 18. Thus, the disks are opposed and pivoted between the limb portions 9 and the respective spacers or adapters 16 are interposed between marginal portions of the disks to maintain the desired coaction and precision-like assembling of parts. The opposed inner surfaces of the respective disks 17 are provided with radially extending eccentrically positioned cam grooves 19 and these serve to accommodate motion transmitting or actuator balls 20. The balls 20 fit and are assembled in semi-spherical depressions or recesses 21 formed in opposite faces of a rectangular motion transmitting and actuating block 22. The block is a reciprocatory unit and includes a reduced neck-like extension which may be referred to as a relatively movable stud 23 since it lines up with the aforementioned relatively stationary stud 12. The stud 23 is also provided with a central screw threaded socket 24 for coaction with the socket 13. What is more, it is provided with calibrations 25 and suitable coacting ordinals.

A thumb wheel is denoted by the numeral 26 and this has its marginal portion milled or suitably knurled for convenient gripping and turning. The grip also carries axially aligned right and left feed screws 27 and 28 and these are threaded into the respective sockets 13 and 24 which are correspondingly threaded. Attached 55 permanently to the wheel 26 and surrounding

each stud is a sleeve and the sleeves are respectively denoted by the numerals 29 and 30 and have bevelled portions 31 which are properly graduated and marked to provide rotary micrometer scales and these coat with the reciprocating micrometer scales 14 and 25 on the aforementioned studs 12 and 23. It follows that we thus have manually operable mechanical means with the parts effectively cooperating and provided with coacting indicating scales, whereby to provide micrometer means between the frame 8 and actuator unit 22, the latter, by way of the cam grooves 19 and coacting balls 20 converting rotary motion into reciprocatory motion and serving to move the legs 15 toward and from each other and at the same time providing accurate measuring facilities. No doubt, the views of the drawings, read singly and collectively and in conjunction with the description will enable the reader to understand the construction and operation of the instrument.

Precise directions for use and examples of various shop practices already well known to those skilled in the art to which the invention appertains need not, it is believed, be herein included.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. A measuring instrument of the class shown and described comprising a frame means embodying spaced parallel resilient limbs, a pair of complementary caliper legs having spaced parallel heads at corresponding ends, one head being disposed in rotary wiping contact with the inner surface of one limb and the other head being disposed in rotary wiping contact with the corresponding inner surface of the remaining limb, the outside surfaces of said heads having median depressions, the coacting inside surfaces of said limbs having corresponding depressions respectively aligned with said first named depressions, anti-friction balls removably seated, one ball in each coacting pair of opposed depressions and pivotally connecting said heads with said limbs, a reciprocable actuator unit fitted slidably between the opposed inner surfaces of said heads, manually adjustable means be-

tween the frame means and actuator unit for regulating the latter, and camming means interposed between said actuator unit and inside surfaces of said heads so that by reciprocating the actuator unit in relation to the heads, said caliper legs are opened and closed.

2. A measuring instrument of the class shown and described comprising a frame embodying spaced parallel resilient limbs connected at corresponding ends and having their opposite ends free and movable toward and from each other, a pair of complementary caliper legs provided at corresponding ends with spaced parallel disk-like heads, said heads having their respective outer surfaces in rotary wiping contact with the adjacent inner surfaces of the respective coacting limbs and being centrally pivoted on said limbs, the adjacent free ends of said limbs projecting beyond the marginal edge portions of said heads and being bolted together, an actuator unit rectangular in cross section and reciprocable in sliding contact between said heads, the inner opposed surfaces of said heads having complementary camming grooves, the coacting surfaces of said actuator having semi-spherical recesses aligned and cooperable with said grooves, there being one groove and one coacting recess on one side of said actuator unit and one groove and one recess on the opposite side of said actuator unit, an anti-friction ball fitted into each groove and its coacting recess to provide cam operating connections between the heads and unit for opening and closing said members, and means interposed between said frame means and actuator for adjusting the latter.
